POLAR ELECTROMAGNETIC RELAY

Petrus Wilhelmus Ter Borg, Friedrich Ludwig Jansen, and Hendrik Johannes de Jong, all of Hilversum, Netherlands, assignors to North American Philips Company, Inc., New York, N.Y., a corporation of Delaware

Filed Aug. 19, 1958, Ser. No. 755,907

Claims priority, application Netherlands Aug. 22, 1957

6 Claims. (Cl. 200—93)

This invention relates to polar electromagnetic relays having a yoke of magnetizable material and an armature of similar material, the yoke being pre-magnetized by at least one permanent magnetic body of material having no electric conductivity and a high coercive field strength, which body is interposed between parts of the yoke. The permanent magnetic body interposed between parts of the yoke may in such relays consist, for example, of a material composed of substantially non cubic crystals of poly-oxides of iron and at least one of the metals barium, strontium, lead and possibly calcium. For such a material see United States Patents Nos. 2,762,777 and 2,762,778.

An object of the invention is to provide a polar relay having one or more permanent magnetic bodies of no electric conductivity, in which the non conductivity of these bodies is utilised to arrive at a simple and compact structure which keeps the cost price low and more particularly may lead to relays of small size.

According to the invention, the armature and at least one part of the yoke, which is electrically separated from the other parts of the yoke by means of an interposed permanent magnetic body, have co-acting contact surfaces, the current being supplied to these contact surfaces through the armature and the relevant part of the yoke, respectively. In one preferred embodiment of the invention, the relay is designed as a bipolar relay, the armature of which is held alternately in either of its extreme positions by the pre-magnetization. In such a relay according to the invention, the armature is surrounded by an energizing coil and has one extremity pinched between two permanent magnetic bodies magnetized in the same direction, to each of which adjoins a part of the yoke extending substantially in the direction of length of the armature, which parts of the yoke, located on different sides of the armature, at the level of the other extremity of the armature, have electric contact surfaces with which a contact surface of the armature alternately co-acts.

In a further preferred embodiment of the relay according to the invention, the armature is so designed that its magnetic reluctance is low and, for this purpose, the armature comprises a small strip of flexible metal provided, at least on one side, with two rigid plates of magnetizable material extending in line in the direction of length of the strip, a portion of one plate which bends off the strip overlapping the adjacent end of the other plate, thus forming an airgap between these plates, which permits of a movement of one plate with respect to the other by flexion of the part of the flexible strip located between the plates.

In order that the invention may be readily carried into effect, one embodiment will now be described in detail, by way of example, with reference to the accompanying drawing in which:

Fig. 1 is a longitudinal section, and

Fig. 2 is a plan view of an embodiment of the relay according to the invention in the form of a bipolar relay.

2

The relay shown has a yoke constituted by two parts 1 and 2 of the same shape, each constituted by a soft-iron strip. Each strip is rectangularly bent four times, so that its ends are located approximately in the same plane. Placed between the extremities 3 and 4 of the two strips are two non-conductive plates 5 and 6 of permanent magnetic material, which are magnetized in the same direction. A permanent magnetic material suitable for the plates 5 and 6 is composed of substantially non-cubic crystals of poly-oxides of iron and at least one of the metals barium, strontium, lead and possibly calcium.

One extremity of the armature 7 of the relay is pinched between the plates 5 and 6. The armature comprises a thin strip of flexible metal 8, for example of Phosphor bronze, the pinched extremity of which and a further part have soldered to them, on each side, a thin soft-iron strip 9, 10 respectively.

The stacked parts of the yoke, the armature and the permanent magnetic bodies 5 and 6 are clamped together by means of a paper ribbon 20 tautly wound round this stack, which ribbon prior to winding was impregnated with a hardenable synthetic resin, for example a phenol-formaldehyde resin. This resin is hardened after winding the ribbon 20 round the stack.

The free extremity of the armature, which extends between the ends 11 and 12 of the parts 1 and 2 of the yoke, is provided with two short soft-iron strips 13 and 14, which are secured, for example welded, to the flexible strip only at the ends adjacent the pinched part of the armature. These ends of the strips 13 and 14 are overlapped with some play by upwardly-bent parts 15 and 16 of the soft-iron strips 9 and 10.

The armature 7 is surrounded by an energizing coil 17, the coil former 18 of which is maintained in position by the parts 1 and 2 of the yoke.

The extremities 11 and 12 of the parts 1 and 2 of the yoke are correctly spaced apart due to their being pressed into a small block 19 of insulating material, preferably of synthetic material having a high internal damping, such as polyester isocyanate. Due to their dovetail form (see Fig. 2), the extremities 11 and 12 are rigidly held in the block 19. The block 19 not only spaces apart the extremities of the parts 1 and 2 of the yoke, but also reduces any rebound tendency of the contacts.

The extremities 11 and 12 of the parts 1 and 2 of the yoke are provided, on the side adjacent the armature, with slightly circular electric contact surfaces 21 and 22 obtained by depression of the yoke parts and with which the strips 13 and 14 of the armature 7 can co-operate.

This is possible due to the thin metal strip 8 of the armature, between the areas where this strip is strengthened by the soft-iron strips 9, 10 and 13, 14 having a non-strengthened part 23, which is readily flexible, thus permitting either the soft-iron strip 13 to engage the contact surface 21 or the soft-iron strip 14 to engage the contact surface 22. In each of said positions, the armature is held by the pre-magnetization of the relevant part of the yoke provided by one of the permanent magnetic bodies 5 and 6.

The magnetic flux which passes in the direction of length through the armature 7 meets with low resistance in this armature due to the upwardly-bent parts 15 and 16 of the soft-iron strips 9 and 10 forming a comparatively narrow air-gap with the soft-iron strips 13 and 14.

The lower extremities of the parts 1 and 2 of the yoke and the armature 7, extending beyond the permanent magnetic bodies 5 and 6 are each connected to one of the lead-through pins 27 fixed in the base 28 of a glass bulb 29 surrounding the relay. The base 28 also contains two lead-through pins which are electrically connected to an end of the energizing winding 17 such, for

example, as 30. The pins in the base 28 are grouped so as to fit into the apertures of a tube holder for a subminiature electron tube. The bulb 29, after the relay being mounted therein, may be evacuated, but it is alternatively possible to use a filling with a suitable gas, for instance an inert gas.

To ensure satisfactory contact between the strips 13 and 14 of the armature and the contact surfaces 21 and 22 of the free extremities of the parts 1 and 2 of the yoke, these parts are preferably covered with a layer of noble metal, for example rhodium or silver.

The length a of the relay described by way of example is actually only about 41 mms., from which it readily appears what small dimensions may be obtained with the structure according to the invention. This relay may substitute a trigger circuit, since the armature may be caused to tilt over by means of the discharge current of a capacitor through the energizing winding 17.

What is claimed is:

1. A polarized relay comprising a yoke including two spaced opposing portions each of a magnetizable electrically conductive material, an armature of magnetizable material resiliently mounted between the opposing spaced portions of the yoke, a body of electrically insulating permanent magnet material interposed between the portions of the yoke and the armature, said armature being positioned to engage an opposing surface portion of the yoke thereby making an electrical connection between the armature and one of the opposing spaced portions of the yoke, and terminal means connected to said armature and said spaced opposing portions of the yoke for completing an electrical connection through said armature and said yoke.

2. A polarized relay comprising a yoke including two opposing portions each of a magnetizable electrically conductive material, an armature of magnetizable material resiliently mounted between the opposing spaced portions of the yoke, an energizing coil surrounding a portion of the armature, two bodies of electrically insulating permanent magnet material clamping the armature between and separating the armature from the portions of the yoke, each of said bodies being magnetized in the same direction, said armature being positioned to alternately engage opposing surface portions of the yoke thereby making an electrical connection between the armature and one of the opposing spaced portions of the yoke, and terminal means connected to said armature and said spaced opposing portions of the yoke for completing an electrical connection through said armature and said yoke.

3. A polarized relay comprising a yoke including two opposing portions each of a magnetizable electrically conductive material, an armature resiliently mounted between said portions of said yoke and comprising a thin flexible metal strip, two rigid plates of magnetizable material extending in the direction of length of said strip, a portion of one plate bending off the strip and overlapping the adjacent extremity of the other plate thereby forming an air-gap between said plates which allows movement of one plate with respect to the other by flexion of the portion of the strip between the plates, an energizing coil surrounding a portion of the armature, two bodies of electrically insulating permanent magnet material clamping the armature between and separating the armature from the portions of the yoke, each of said bodies being magnetized in the same direction, said armature being positioned to engage an opposing surface portion of the yoke thereby making an electrical connection between the armature and one of the opposing spaced portions of the yoke, and terminal means connected to said armature and said spaced opposing portions of the yoke for completing an electrical connection through said armature and said yoke.

4. A polar relay as claimed in claim 3, in which the two parts of the yoke extend beyond the contact surfaces of the armature and are fixed in a small block of insulating material transverse to the direction of length of the armature.

5. A polar relay as claimed in claim 2, in which the assembly comprising the part of the armature clamped between the permanent magnetic bodies, said bodies and the adjoining parts of the yoke are clamped together with a ribbon of insulating material wound around said parts of the yoke, said ribbon being impregnated with a hardened synthetic resin.

6. A polar relay as claimed in claim 2, in which the assembly is housed in a gas-tight envelope, for example of glass, the base of which is provided with a plurality of lead-through pins, which are electrically connected to the energizing coil, the armature and those parts of the yoke which carry an electric contact surface.
